UNITED STATES PATENT OFFICE

99,645

DESIGN FOR A CARTON

Arthur E. Macon and Walter J. Weir, Scarsdale, N. Y., assignors to Container Corporation of America, Chicago, Ill., a corporation of Delaware

Application January 4, 1936, Serial No. 60,425

Term of patent 14 years

To whom it may concern:

Be it known that we, Arthur E. Macon and Walter J. Weir, citizens of the United States, residing in Scarsdale, county of Westchester, and State of New York, have invented a new, original, and ornamental Design for a Carton, of which the following is a specification, reference being had to the accompanying drawing, forming a part thereof.

In the drawing:

The figure is a perspective view of a carton embodying our new and ornamental design.

The sides of the carton opposite those illustrated involve substantially a repetition of the illustrated sides.

We claim:

The ornamental design for a carton, substantially as shown and described.

ARTHUR E. MACON.
WALTER J. WEIR.
